UNITED STATES PATENT OFFICE

2,597,772

INDIVIDUAL NECK DUSTER

Antonio Bongiovanni, Philadelphia, Pa., assignor of fifteen and one-half per cent to Antonio Stango, fifteen and one-half per cent to Antonio Oteri, ten per cent to Alfred Stango, eleven and one-half per cent to John W. Kephart, Jr., and eleven and one-half per cent to A. Evans Kephart, all of Philadelphia, Pa.

Application June 2, 1949, Serial No. 96,809

2 Claims. (Cl. 15—226)

1

This invention relates to an improved individual neck duster especially adapted for use in barber shops, beauty parlors, or similar establishments, for brushing the cut ends of hair from about the neck and face, or in applying talcum powder or the like thereto.

An object of the invention is to provide a device the body of which will be made entirely of paper, and which will be so inexpensive that the duster may be discarded after a single use thereof, to the end that a barber may employ a fresh sterile duster for each customer.

A further object of the invention is to provide a device embodying a unitary handle and dusting tuft, and wherein the handle will be fashioned to impart the necessary rigidity thereto as well as the necessary stiffness to the neck of the device at the region of the junction between the handle and tuft.

And the invention seeks, as a still further object, to provide a device the body of which may be formed from a single blank of paper, and wherein the blank will be so fashioned that simply by winding the blank into a more or less tight roll, the handle and tuft will be produced.

Other and incidental objects of the invention will appear during the course of the following description, and in the drawings:

Figure 1 is a plan view of the blank from which the body of the device is formed.

Figure 2 is an end view of the blank.

Figure 3 is a side elevation of the duster.

Figure 4 is a vertical section through the duster.

Figure 5 is a transverse section on the line 5—5 of Figure 4.

Figure 6 is a fragmentary diagrammatic sectional view showing the plaits of the blank of Figure 1.

Figure 7 is an enlarged, fragmentary, diagrammatic, perspective view of a portion of a single winding of the neck of the duster, broken away transversely at vertically spaced points to show the overlap and taper of the folds of the plaits.

Figure 8 is a fragmentary plan view of the blank of a modified form of the invention.

Figure 9 is an elevation of the modified form of duster.

Figure 10 is a fragmentary diagrammatic sectional view showing the plaits of the blank of Figure 8.

In carrying the invention into effect, I employ an oblong rectangular sheet of paper which is folded medially, longitudinally thereof, to pro-

2

vide a blank 10 of overlapping plies 11 of equal width and length. The paper employed is preferably more or less soft in character although somewhat tough such, for instance, as conventionally used for paper napkins or the like, but is preferably thicker and of more fluffy body than the paper of the usual napkin, the point being, in the present instance, that the paper will not cut or abrade the skin, but will feel soft when 10 against the face or neck.

Adjacent the fold connecting the plies 11 with each other, said plies are provided with imperforate margins 12, while at their opposite margins said plies are each slit transversely along 15 parallel lines to provide a series of preferably narrow dusting strips 13. As will be observed, the strips 13 are of a length substantially equal to the width of the margins 12 of the plies 11.

Adjacent the inner ends of the strips 13, the 20 margins 12 of the plies 11 are creased to provide substantially V-shaped plaits 14 which extend longitudinally of the strips from the inner fixed ends thereof, a plait being provided in conjunction with each strip. Each of these plaits is defined by a pair of fold lines 15 which diverge toward the inner end of the strip straddled thereby to terminate at the inner ends of the slits at the sides of said strip, while a third medial fold line 16 bisects the angle between the fold lines 15. Thus, triangular folds 17 are provided 25 between the fold lines 15, which folds may be caused to overlap.

As seen in Figures 3, 4, and 5 of the drawings, the blank 10 of Figure 1 is more or less tightly wound upon itself spirally to produce a roll defining a cylindrical handle 18, formed by the margins 12 of the blank, and flaring from said handle is a dusting tuft 19, formed by the strips 13 of the blank. Securing the blank rolled is a 30 staple or the like 20.

It is now to be observed that as the blank 10 is rolled, the folds 17 of each of the plaits 14 are, as suggested in Figure 6, disposed in overlapping relation. Consequently, the effective 35 length of the blank at the longitudinal area of the plaits is shortened so that a conical neck 21 is formed at the region of the junction between the handle 18 and tuft 19. As will be perceived, the spiral windings of the blank 10 at the neck 21 will, due to the extra thickness provided by the overlap of the folds 17 of the plaits 14, be much tighter than adjacent the free end of the handle 18, and said tightness is increased toward the small end of said neck by the gradual 40 widening of said folds. As a result, the neck is

stiffened and stabilized to not only lend rigidity to the handle 18 so that it may be conveniently grasped and manipulated to accomplish dusting operations with the tuft 19, but also a stable junction between the handle and tuft is provided by the stiffest smaller end portion of the neck so that when manipulating the duster, lateral bending stress at the free ends of the strips 13 of the tuft 19 will not collapse the tuft as a whole relative to the handle. If so desired, the margins 12 of the plies 11 of the blank 10 may be impregnated with a suitable stiffening agent, such as an appropriate plastic, or a suitable adhesive, such as glue or mucilage, may be applied to said margins, the purpose being, in each instance, to 15 stiffen the handle 18 and impart added solidity thereto.

In Figures 8, 9, and 10 of the drawings, I have shown a slight modification of the invention wherein the blank is indicated at 22, the handle at 23, and the tuft at 24. In this instance, the blank 22 is arcuate and is provided with diagonal plaits 25 having folds 26 which serve the same purpose as the folds 17 of the plaits 14. Otherwise, the modified structure is identical with the 25 form of the invention first described, and further explanation is unnecessary.

Having thus described my invention, I claim:

1. An individual neck duster including a body one end portion of which provides a handle and the opposite end portion of which is composed of a bunched series of strips providing a tuft integral with the handle, said body being formed of a paper roll having spiral windings, tapered plaits formed in said windings at the inner ends of said strips at the handle-portion of the body and gradually widening in a direction longitudinally of the strips toward the inner ends thereof as well as successively overlapping to provide the

inner end portion of said handle with a tapered neck gradually stiffened by the widening plaits toward the inner end of said tuft, and means securing said windings rolled.

5 2. An individual neck duster including a body one end portion of which provides a handle and the opposite end portion of which is composed of a bunched series of strips providing a tuft integral with the handle, said body being formed of a paper roll having spiral windings formed at corresponding margins thereof with slits defining said strips and being provided adjacent the inner ends of said strips at the handle-portion of the body with V-shaped plaits straddling the inner ends of said strips and widening in a direction longitudinally of the strips toward the inner ends thereof as well as successively overlapping to provide the handle with a tapered neck gradually stiffened by the widening plaits toward the inner end of said tuft, and means securing said windings rolled.

ANTONIO BONGIOVANNI.
